O. KNAPP

UMBRELLA

Filed May 20, 1927

UNITED STATES PATENT OFFICE.

OTTO KNAAPP, OF NEW YORK, N. Y.

UMBRELLA.

Application filed May 20, 1927. Serial No. 193,042.

This invention relates to umbrellas and in particular to a type adapted to be collapsed and for transport in the pocket or handbag of the user.

5 A particular object of the invention is to provide an umbrella which is of unitary construction and which may be folded or collapsed into a very compact bundle so that it may be easily carried about or in a handbag and will be ready for use readily and without the necessity of assembling the same.

A still further object of the invention is to provide an umbrella, the cover supporting ribs and handle of which are made out 10 of tubular members, held together in extendible relation so that the entire structure may be collapsed within itself to provide a compact bundle.

To enable others skilled in the art to fully 20 comprehend the underlying features of my invention that they may embody the same in the various modifications in structure and relation contemplated, a drawing depicting a preferred form has been annexed as a part 25 of this disclosure and in such drawing, similar reference characters denote corresponding parts throughout all the views, of which,

Figure 1 is a view in side elevation of the umbrella in its open position showing the 30 handle thereof extended in position ready for use.

Figure 2 is a view looking at the inside of the umbrella and showing the relation of the ribs and the rib-supporting elements.

35 Figure 3 is a view of the umbrella shown in its collapsed position and ready to be placed in a suitable bag or container, so that it can be transported in the pocket or in a travelling bag.

40 Figure 4 is an enlarged fragmentary view looking into the umbrella, the section being taken through the uppermost tubular member of the handle construction and showing the locking washer which retains the fabric supporting ribs in their extended position.

45 Figure 5 is a fragmentary view in sectional elevation, the same being enlarged to show the details of construction of my improved umbrella.

50 Figure 6 is a fragmentary side view of the locking means used to retain the sections of the handle in their extended relation, and

55 Figure 7 is a modified form of handle, the end of which is adapted to hold ornamental features which particularly adapt the umbrella for the use of women.

Referring to the drawings in detail, 5 indicates the usual fabric umbrella covering which is connected at spaced points in its periphery to the fabric supporting ribs, the latter of which, as shown in Figure 2, are made from two sections of tubing, the inner section 6 being slightly larger in diameter than the outer section 7 and being adapted to allow the outer section 7 to slide therewith when the umbrella is to be collapsed. The outer sections 7 are provided with the ornamental knobs 8 to which the fabric cover 5 is secured as by sewing 6, or in any other manner desired. The outer rib members 7 60 are each provided with a resilient latch 9 which extends through a suitable slot in the outer tube 7 and extends down into the tube, where it is held through the medium of a crimped portion 10; the end of the latch 11 65 being positioned in a suitable bore in the tube 7, so that displacement thereof is prevented but yieldable movement of the latch end 9 thereof is allowed. It is of course understood that the latch 9 will normally 70 project through the opening in the tube so that it engages when permitted to do so, the outer end of the tubular members 6, in which the tubular member 7 has sliding movement. In collapsing the fabric holding ribs, it is 75 simply necessary to depress the latches 9 and push the tube 7 into the tube 6, this of course will loosen the fabric which is not secured to the ribs, in any other manner, and if necessary, may be taken off and laundered. 80

The ribs 6 are positioned between an outer washer 12 and an inner spider 13, there being held between the two, a suitable hinge plate 14 which is slotted to receive the reduced end 15 of the tubes 6, it of course 85 being understood that these tubes are flattened at one end to provide the reduced portions, which are pivoted in the hinge plate 14 on a suitable hinge pin 16 which extends around the hinge plate 14 and maintains the tubes 6 in pivoted connection therewith. It is quite evident that washers 17 90 may be used to space the hinge plate 14 from the spider 13 and washer 12 so that the arms 6 will have free pivotal movement 100 when they are manipulated, the spider 13 may be formed integral with the upper end of the uppermost handle tube 18, this tube being arranged to receive the plug 19 at its upper end which has a threaded extension 110 20 that extends to the spider 13, hinge plate 14, and washer 12, the threaded end thereof

being arranged to receive the lock nut 21, which in turn is provided with a ring 22 to facilitate its manipulation.

It is quite evident that in order to allow the rib members 6 and 7 to have folding or pivotal movement with respect to the hinge plate 14 that the plate 14 must be manipulated so that the arms 6 or tubular members will be brought into alignment with the spacer 23 provided by the extension 24 of the spider, there being one of each of these openings 23 provided for each of the tubes 6 so that the same may fall down between the extension 24 to a position parallel with the handle, as illustrated by the dot and dash lines in Figure 5.

In order to support the umbrella, I have made use of a collapsible handle 23 which consists of the upper tubular member 18, intermediate tubular member 24 and lower member 25, the latter of which is adapted to receive the member 24 while the member 24 is adapted to receive the member 18.

The lower end of the tubular member 25 may be closed by a suitable plug 26 so that in collapsing, the member 24 will not slide out of the tubular member 25 and to also give the handle a finished appearance.

In order to allow for the proper extension of the members 18, 24 and 25, I have provided on the lower end of each of the members 18 and 24, a limiting nipple 27 or ferrule and have also reduced the ends of the tubes 25 and 24 so that they fit snugly about the adjacent tubes 24 and 18 respectively, and will not slide over the ferrules 27. This reduction of the diameter of the tube 24 is illustrated in Figure 5 and indicated by the numeral 28, the extension 28 being also flattened as at 29 in each instance to receive the latch end 30 of a suitable spring piece 31, which is secured in the tubes 18 and 24 and arranged to extend to a suitable opening therein so that the latch piece 30 will prevent collapse of the tubes 18 and 24 into each other and into tube 25 when the same have been drawn apart to the position shown in Figure 1.

The slot 29 will of course be engaged by the latch piece 30 so that relative rotation of the parts 18, 24 and 25 will be prevented.

When it is desired to open the umbrella, the umbrella is inverted and the cover supporting ribs drawn down so that they are limited in their pivotal movement by the washer 12 at which time the handle 23 may be revolved to bring the flat portions 24 or extensions of the spider into position over the tubular members 6 at which point the nut 21 is tightened up and the tubular members 26 are retained in their proper position, as shown in Figure 2, and of course, cannot collapse or have movement on their pivotal points. The handle parts are then drawn upon with the result that the pieces 18, 24

and 25 are extended their full length and are automatically locked by the latch pieces 30 snapping into position. The ends of the cover supporting ribs are then drawn upon to complete the umbrella, although it is understood that any of the operations may take place depending upon the desire of the user, that is, the ribs may be extended to their full position first and then the cover revolved to bring the rib members 6 into position beneath the extensions 24 of the spider after which they can be locked in place and the handle extended.

In Figure 7, I have shown a modified form of locking nut and handle knob, which especially accommodates the umbrella for use by women and adds to its ornamental appearance and in this respect, I have provided an elongated nut member 32 which is adapted to be threaded over the shank 20 to lock the spider and adjacent parts together, and to the lower end of the tubular member 25 of the handle 23, I secure the socket member 23 having an opening 34 therein which is arranged for the accommodation of the carrying strap 35 for convenience in handling, the end of the plug 33 being enlarged, if desired, as at 36, to give the same an ornamental appearance.

It is evident, therefore, that I have provided an umbrella which may be collapsed and the ribs of which may be collapsed for storing the device in a small space, in fact, the collapsing of the umbrella parts adapts the same to be carried in the pocket of the user so that it can be used in an emergency.

It is evident, also, that I have provided an umbrella having no loose parts, or parts to be assembled when the same is to be used which can become lost or separated and I have also provided an umbrella which can be assembled ready for use in a minimum of time and with a minimum of trouble.

It is also evident that my improved construction dispenses with the usual bracing or supporting ribs which extend from the handle to the main ribs thereby allowing the umbrella to be carried lower.

While I have illustrated and described my invention with some degree of particularity, I realize that in practice various alterations therein may be made. I therefore reserve the right and privilege of changing the form of the details of construction or otherwise altering the arrangement of the correlated parts without departing from the spirit of the invention or the scope of the appended claims.

Having thus described my invention what I claim as new and desire to secure by United States Letters Patent is:—

1. A foldable umbrella comprising a handle and ribs, a disk having openings therein formed on the handle, a ring disposed above said disk and to which the ribs are pivoted,

and said disk being movable relatively to said ring, so that the openings in the disk are in alignment with the ribs of the umbrella whereby the latter may be folded to a 5 position alongside the handle.

2. A foldable umbreila comprising a telescopic handle and telescopic ribs, a disk having slot-like openings therein formed on the handle, a ring disposed above said disk and 10 to which the ribs are pivoted, said disk being movable relatively to said ring so that the openings in the disk are in alignment with the ribs of the umbrella whereby the latter may be folded to a position alongside 15 the handle and a locking member for securing the disk and ring together.

3. A foldable umbrella comprising a sectional, tubular handle and tubular ribs, the

parts of each of which telescope and each of which have latch openings therein, a latch 20 for holding the parts in extended position, means for preventing relative rotation of the handle parts when latched in their extended position, a disk having slot-like openings 25 therein formed on the handle, a ring disposed above said disk and to which the ribs are pivoted, said disk being movable relatively to said ring so that the openings in the disk are in alignment with the ribs of the umbrella whereby they may be folded 30 to a position alongside the handle and a locking member for securing the disk and the ring together.

In testimony whereof I affix my signature.

OTTO KNAPP. [L.s.]
